DESIGN FOR A PERFUME CONTAINING PENDANT OR THE LIKE

William C. Frommer, Yonkers, N. Y.

Application August 18, 1939, Serial No. 86,777

Term of patent 3½ years

To all whom it may concern:

Be it known that I, William C. Frommer, a citizen of the United States, residing at 28 Purser Place, Yonkers, in the county of Westchester and State of New York, have invented a new, original, and ornamental Design for a Perfume Containing Pendant or the Like, of which the following is a specification, reference being had to the accompanying drawing, forming part thereof.

In the drawing

I claim:

The ornamental design for a perfume containing pendant or the like, as shown.

WILLIAM C. FROMMER.
